Specification of Letters Patent. Patented Apr. 13, 1915.

Application filed February 28, 1911. Serial No. 611,312.

To all whom it may concern:

Be it known that we, KIRBY S. REIST and STERLING B. BATSFORD, both citizens of the United States, residing at Berkeley, in the county of Alameda and State of California, have invented new and useful Improvements in Type-Casting Machines, of which the following is a specification.

This invention relates to type casting machines, and especially to linotype machines.

The invention comprehends the general improvement, simplification and increase of capacity of linotype machines in which are employed suitable matrices caused to traverse the several component mechanisms to the end of producing a composed type bar.

Manifold attempts have been made to obtain means for greatly increasing the variety of fonts or faces of type, in this class of machines, from which the operator might compose a form. The first attempt to provide for this variation was to supply extra magazines containing different fonts; later, double magazine machines were introduced, and also two-letter matrices were employed and recently it was proposed to use a multiplex magazine. This last mentioned scheme is complex and expensive, involving as it does, a series of escapements and a separate distributor for each magazine.

Generally, the object of our invention is to provide a multiple magazine structure adapted to carry a selected matrix magazine into operative relation with a single escapement mechanism and distributor; to provide an escapement mechanism adapted to be moved to and from operative relation with a magazine; to provide means for locking the magazine structure against premature movement; to provide instrumentalities for actuating the magazine structure; and devices for locking the structure; to provide an actuator for the escapement mechanism, and to provide means controlled by said actuator for temporarily sustaining the matrices in their respective channels of the several magazines.

It is also a purpose of our invention to devise means whereby the magazine structure or carriage, as it will hereinafter be designated, will be under a mechanical control, preventing the movement of the carriage be-

fore the distribution of such of the matrices as are in the course of distribution, and also to provide an improved means for operating the second elevator for linotype machines.

An important object of our invention is to provide an improved escapement or verge whereby the escape of certain pieces from a magazine or container may be accurately controlled, and which escapement or verge increases the velocity or rapidity with which the escape of the pieces may be obtained.

The invention consists of the parts and the combination and construction of parts as hereinafter more fully described and claimed, having reference to the accompanying drawings, in which—

Sheet 1—Figure 1 is a side elevation of the machine showing the superposed carriage and elevator. Fig. 2 is a detail view of the elevator. Sheet 2—Fig. 3 is a front elevation of the magazine carriage and assembler mechanism. Fig. 4 is an end view of the elevator. Fig. 5 is a detail view showing the elevator bar in the uppermost position. Fig. 6 is a fragmentary detail of the elevator trip. Figs. 7 and 8 are modified forms of the elevator rail. Sheet 3—Fig. 9 is a side elevation of the sliding carriage and its actuating train. Fig. 10 is an enlarged detail view of the carriage governor.

Fig. 11 is a sectional detail view of the carriage operating spindle and its lock.

Sheet 4—Fig. 12 is a side view of the magazine structure or carriage removed from the machine. Fig. 13 is a horizontal section through a portion of the carriage showing a series of magazines in position, and showing the actuator and the escapement in plan and partly in section.

Sheet 5—Fig. 14 shows a portion of the magazine carriage and the escapement and its actuator elevated for cooperative engagement with the matrices in a magazine. Fig. 15 is a detail side-elevation of the rotary escapement wheel and the actuator rack engaging and unlocking the magazine-lock bolt.

Sheet 6—Fig. 16 shows a portion of the magazine carriage and the escapement mechanism carried into lower position by its actuator.

Fig. 17 is a detail view showing the escape-wheel and its relative verge in the lower position and locked to prevent movement. Fig. 18 is a perspec-

tive view of the escape-wheel and its verge of one of the magazine channels in lowered and locked position.

In the present embodiment of our invention, A represents magazines formed with a plurality of channels 2, adapted to contain several sets of matrices 3 which are adapted to escape as selected from their respective magazines and travel through an assembler 10 entrance B, Fig. 3, and collected in a movable elevator or stick G from which they are eventually carried over into position in front of a casting mechanism, not necessary to be here shown, from which they are then 15 shifted to an elevator C. This elevator C, which will be hereinafter more fully described, carries the matrices upwardly to a distributor bar D, supported upon the frame E of the machine. From this distributor 20 bar D the matrices are deposited in their respective channels in the proper magazine.

To the end of accomplishing the desired advantage of enabling an operator to select one of a number of various fonts or faces 25 of matrices without leaving the operator's chair to remove one magazine and insert another containing the desired font, or without limiting the capacity of a machine by superposing, in a fixed structure, several 30 magazines, and without necessitating the entire reconstruction of a linotype machine, and increasing its complexity by adding extra distributors and escapement mechanisms, we propose to mount upon the frame of the 35 machine a carriage F of appropriate design and form, provided with a series of slide-ways 4 into which may be removably inserted magazines A.

Manifestly, the carriage F may be so constructed that the magazines, which may be 40 in any desired number, can stand vertically, as shown, or may be inclined, if desired, and by building the carriage F of such proportions to allow the use of a plurality of 45 magazines, the operator has only to shift the carriage to select the desired font without leaving the operator's chair. In order to render the shifting of the carriage both 50 easy and simple, there is mounted upon its lower rails antifriction devices, as rollers 5, traveling upon supporting ways 6 of the frame E of the machine; and to one side of the carriage at its lower portion, is attached or formed a rack 7 adapted to mesh 55 with a gear 8, Fig. 9, supported in suitable journals in the frame, and driven by a bevelled gear or other appropriate elements 9, secured upon the upper end of a shaft 10, having upon its lower end a transmission 60 member 11, meshing with a complementary member or gear 12, secured upon a spindle 13. Upon this spindle, and adjacent the gear 12, is a spur or other suitable transmission gear 14, and at its outer end is secured 65 an index finger 15, adapted to register

with suitable notches formed in a dial 16, supported upon the bearing or the frame in which the spindle 13 is mounted. Thus, when the spindle 13 is turned, the gears 12 and 11 transmit power to the rack-engaging gear 8, thus advancing or receding the slideable carriage F upon its ways 6 to carry a magazine A into position below the distributor bar D. By so enabling the operator to advance or retract the carriage to bring 75 any one of the magazines A into position so that its matrices can be employed, we are able to employ but one distributor bar, which may be of the standard or well known form now in common use on linotype machines.

It is necessary that the carriage F be locked in position to cause the proper alignment of a magazine below the distributor bar D, and to prevent movement of the carriage while there are sustained and being distributed from the bar D any matrices of such a font as designed to go into a particular magazine, which should then be in proper position below the distributor.

We have provided a simple, reliable and automatically operable mechanism to detect the presence of a matrix upon the bar in the event that the operator should attempt to shift the carriage prematurely, and which mechanism also provides means for locking and unlocking and advancing and receding the carriage F. This detecting mechanism, which will hereinafter be referred to as a governor, comprises a member having a pair 90 of spaced parallel blades 17 suspended by hangers 18 from pins 19 which are mounted in each lever-arm 20. The hangers 18 are pivoted upon the pins 19, and are adapted 95 to embrace the distributor D with sufficient 100 freedom to allow blades 17 to move vertically so that their lower edges may, when descending, engage the upper prongs of any matrix or matrices 3 which should happen 105 to be suspended on the distributor bar D. The lever-arms 20, which support the transverse blades 17, are secured on a rock shaft 21 pivoted in bearings formed upon the frame of the machine, and to the outer end 110 of one of the levers 20, is connected a depending link 22, to the lower end of which is secured a plate 23, having a substantially circular perforation 24, communicating with 115 which is a rectangular recess 25, in which is turnable a cylindrical stem 26 rotatably and 120 slidably supported in suitable journals of the frame E.

Formed upon that end of the stem 26, which is adjacent the link-plate 23, is a head portion 27, having angular sides of 125 such proportion that when the stem 26 is pulled forwardly by its handle 28, the members are interlocked so that the stem 26 cannot be turned. There is secured to or formed upon the lower portion of the link 22, a 130

shoulder 29, normally adapted to rest upon an arm 30 of a bell crank pivoted at 31, to the frame E. The lower arm of the bell crank is yoked and embraces a collar 32, secured upon the stem 26, and in operation when the operator pulls on the handle 28, the yoked bell crank will rock and allow the link 22 to descend and permit the controller blades 17 to slide downwardly along the distributor bar D until they encounter a matrix 3, should one be in position on the distributor. Should there be one or more matrices on the distributor to prevent the controller blades 17 from descending, the downward movement of the link 22 will be prevented, and so long as the operator is pulling on the stem 26 so that the portion 27 is in engagement with the walls of the slot 25, he is unable to revolve the stem 26.

Upon each side of the distributor bar D, are placed distributor screws 33, having the function of advancing the matrices along the bar, and it is necessary to prevent injury to the matrices 3 by the pressure of the controller blades 17 thereon while the screws 33 are being revolved, and in order to protect the matrices against injury from this source, there is pivoted adjacent one lever arm 20 a pawl 34 having a wearing point 35 adapted to drop into the path of rotation of a cam-wheel 36, forming a portion of a clutch 37 mounted upon a shaft 38, which carries a pulley 39, from which power is transmitted by gears 40 to drive the screws 33. The pawl 34 is provided with a slot 41 which embraces a pin 42 carried by a lever-arm 20, and when the operator pulls on the stem 26, rocking the bell crank 30, the lever-arm 20 carrying the pin 42, will drop slightly and permit the point 35 of the pawl 34 to engage the cam wheel 36, causing this latter to be moved outwardly, carrying the clutch plate 37 out of mesh with the pulley wheel 39 and resulting in the stopping of rotation of the screws 33. A very slight downward motion of the pawl 34 will effect the stopping of the screws 33, thereby ceasing the advance of such matrices as may be on the distributor bar D, and the further downward movement of the pin-carrying lever arm 20 will allow the governor blades 17 to rest upon the upper portion of the matrices, should there be any on the bar D, and these matrices consequently stop further lowering of the link 22. Should there be no matrix on the distributor bar D, the governor blades 17 will slide uninterruptedly down its sides, allowing the link 22 to descend sufficiently to carry the perforated plate 23 down to disengage the stem 26 from the slot 25 and align the perforation 24 centrally about the stem 26 so that the angular end 27 could be freely rotated in the plate 23 while the operator is pulling on the handle 28.

Assuming that all of the matrices have been released from the distributor bar D and the operator wishes to shift the carriage F to select a font from another magazine A, he grasps the handle 28 of the stem 26 and turns it for the purpose of lowering an escapement mechanism, which will be more fully hereinafter described, and then pulls on the handle 28 causing the bell-crank 30 to oscillate and allow the link 22 and its lever-arm 20 to fall, thereby disengaging the driving clutch 37 from the pulley 39, stopping the rotation of the gears 40 and screws 33 and shifting forwardly a gear 14' secured on the spindle 26 until it engages the gear 14 fastened on the spindle 13; then by turning the handle 28 power is transmitted from the gear 14', gears 11 and 12, to gear 8 to move backwardly or forwardly the slidable carriage F until the desired magazine A is carried into position below the distributor bar D, in which position the carriage can be locked by a bolt 43, Fig. 14, which is connected to the longer end of a lever 44, mounted upon a pivot 45 supported upon the frame of the machine, and which lever 44 is provided on its shorter end with a pin 46 engaging an internal cam 47, fastened upon an actuator shaft 48, suitably supported in bearings 49. The shaft 48 has secured upon one end a suitable gear 50, meshing with another gear 51, which is secured upon a vertical shaft 52, having secured upon its lower end a gear 53 driven by a gear 54 loosely mounted upon said spindle 26, the hub of the gear 54 being notched, as at 55, to receive a clutch member 56, fastened to the stem 26. So long as the operator is pulling on the operating stem 26, the latter may be revolved without turning the gear 54 by reason of the disengagement of the clutch 56 from the hub of the gear 54, and when he has released the stem 26 a spring 57 coiled thereon automatically closes the clutch 56 so that the gear 54 can be revolved. By revolving the gear 54 power is transmitted through the shaft 52 to the shaft 48, thus rocking the lever 44 and lifting the bolt 43, which is guided in the way 6 into a socket 42' formed adjacent the magazine guide 4 in the bottom member of the carriage F. Preferably, each side of the carriage is locked by bolts 43 and there are as many of the bolt-sockets 42' formed in the carriage as there are magazines, and when the carriage is shifted to a predetermined point, such as is indicated on the dial 16, a pair of these sockets will register above the locking bolt 43.

An important and distinctive provision of our invention is the mechanism whereby the escapement of the several matrices from the magazine can be accomplished by a simple and single escape mechanism, which can be actuated at the proper time to be

engaged and disengaged with a selected magazine without necessitating the operator leaving his position at the keyboard of the machine. The escapement mechanism in the 5 present embodiment comprises a series of matrix-actuated escape-wheels 58 provided on their peripheries with suitably spaced and designed teeth 59, Fig. 18, the several escape wheels being loosely supported upon 10 an arbor 60, mounted in cheek plates 61, connected, in addition to the arbor 60, by a transverse rod 62 upon which are loosely mounted a number of oscillating verges 63 coöperating with their respective escape 15 wheels 58. The ends of the members 60 and 62 project beyond the cheek-plates 61, and are secured in end-plate 64, which bear upon the outside of brackets 65, suitably fastened to the frame E, and which are provided 20 with cam-slots 66, the lower portions of which are substantially straight, and the upper portions of which are inclined upwardly and forwardly, as at 67, and forwardly curved on one side, as at 68. Between 25 the cheek-plates 61 and the cam brackets 65 there is formed a space of sufficient width to receive lever-plates 69, one of which is secured adjacent each end of the actuator shaft 48, and which are provided 30 with internal cams 70, embracing the lower rod 62 of the structure forming a basket supporting the verges and escape wheels. The members going to form this basket comprise the arbor 60, the rod 62, the cheek- 35 plates 61, and the small end-plate 64, slideable upon the outside of the cam brackets 65.

Referring particularly to Fig. 16, it will be observed that the locking bolt 43 has been lowered from engagement with the bottom 40 portion of the carriage F, and that one of the magazines has been moved into position above the lock, and that the shaft 48 has been turned to carry downwardly the cam- 45 plates 69, and that the basket rod 62 has been drawn downwardly through the cam-slot 66 in the bracket 65 by reason of the incurving of the cam slot 70, which embraces the rod 62. Upon actuation of the shaft 48 by the hereinbefore described gears 50 and 50 51, the pin 46 in the lever 44 is depressed, thus elevating the bolt 43 and locking the carriage F, and the rod 62 is lifted by the walls of the cam 70, thus elevating the basket structure through the cam slot 66 55 into the position indicated in Fig. 14, which carries the escape wheels 58 into registration with the rear side of a magazine A, so that one of the teeth 59 will project through an opening formed for its reception in the 60 magazine wall, there being one of these openings to receive the teeth 59 of an escape wheel 58 for each column of matrices in the magazine. The teeth 59 are adapted to project sufficiently into the magazine to encounter the upper shoulder α of each matrix

as it travels out of the magazine. For the purpose of preventing all of the matrices from falling from their magazines when they are shifted, there is mounted adjacent to the lower end of each magazine, a longitudinally extending rotary key or support 70 71 universal to all the magazines in its magazine, which is concaved or channeled, as at 72, and provided at one end, Fig. 15, with an interrupted pinion 73, adapted to be engaged by an annular rack 74, formed upon the periphery of one of the basket actuating cam plates 69. The end of the rotary matrix-supporting key opposite to the one on which is mounted the pinion 73, is flattened angularly at 75, and projects sufficiently beyond the adjacent end of the magazine A to receive a pawl 76, which is pivoted at 77 on the magazine and provided with a shoulder 78 adapted to rest against the flat surface 75 of the rotary key 71, which position is clearly shown in Fig. 16. When the key 71 has been rocked to the position to be locked by the pawl 76, the rear curved surface projects substantially into 80 the magazine to intercept and support the superposed columns of matrices 3, thereby preventing their accidental escape from the magazine. After the operator has actuated the operating stem 26 to select a certain 95 magazine, the actuator levers 69 are swung upwardly, lifting the escape-wheel carriage by means of the bar 62 and simultaneously locking the carriage F and carrying a pin 79, which is fastened in a projection 80 100 formed on one of the cam plates 69, into register with a downwardly curved slotted arm 81, forming a portion of the key-locking pawl 76. As the pin 79 swings into engagement with the curved arm 81, the latter 105 is gradually turned about its fulcrum 77 and lifted off of the rotary key 71, and at the instant the key is freed, the annular rack 74 on the other actuator plate 69, runs into mesh with the interrupted pinion 73 of the 110 key 71, thus rotating the key sufficiently to turn the concaved or channeled portion 72 inwardly, thus clearing the passageway so that the matrices can be released successively from the magazine. The curvature 115 of the internal cam 70 is such that the verge 63 and its associated escape wheel 58 for each matrix channel will be elevated into the position shown in Fig. 15, long before the matrix-sustaining key is turned to release the matrices. When the escapement mechanism comprising the verges and the escape wheels have been carried into operative association with one of the magazines 120 A, and the rotary key 71 turned, the matrices 125 3 will be supported upon the upper radial face of the teeth 59 of the escape wheels 58, and the rotation of the escape wheel 58 under its load of matrices is prevented, by the verge-prong 68', which swings upwardly to 130

engage the rear portion of its associated wheel tooth 59. The operation of any of the tiltable verges 63 is accomplished by means of suitably supported reeds 82, Figs. 14; 15, which may be vertically actuated by respective levers 83 fulcrumed at 84 and provided with suitable keys 85.

A particular and peculiar feature of the present invention is in so forming the verges 63 that they will automatically disconnect themselves from the reeds 82 as the carriage structure is actuated by the operator. The coupling and uncoupling of the several reeds and verges are accomplished by providing the upper ends of the reeds with pins 86, adapted to slip into mesh or engagement with downwardly and rearwardly projecting hooks 63^a of the verges. When the verges have been elevated, as in Fig. 14, the pins 86 assume a position in their respective verges, as shown in dotted lines in this figure, and when the escapement carriage has been depressed so as to clear the carriage F when this is to be shifted, the reed pins 86 are disengaged and the verge hooks 63^a are carried downwardly and rearwardly to the position shown in Figs. 16 and 17. The accidental rotation of the several escape wheels 58 upon their arbor 60 is prevented by means of a shifttable latch 87 which is supported for transverse movement in and across the cheek plates 61 of the basket. The cheek-plates 61 are slotted, as at 88, to permit the transverse movement of the latch 87 by means of dogs 89 pivoted at 90 upon the inside faces of the cheek-plates 61 and provided with eccentric slots 91 embracing the latch 87. The lower ends of the dogs 89 are provided with open curved slots 92 into which may be moved inwardly projecting pins 93 secured upon the actuator plates 69. The relative position of the latch 87 to the teeth 59 of the escape wheels 58 is such that when the dogs 89 are swung about their pivots 90 by reason of the engagement of the pins 93 with the walls of the slots 92, as the pins 93 are turned downwardly the dogs 89 will swing to carry the latch 87 inwardly between a tooth 59 of the escape wheel 58 and an ear 94 formed on the verge 63.

When the escapement mechanism has been carried to the lower position, as indicated in Fig. 17, the dogs 89 will have swung downwardly about their pivots 90 and carried the latch 87 inwardly between a tooth 59 and the ear 94, thus pressing upwardly the point 63^a of the verge 63 and firmly locking all the wheels 58 and all the verges 63. This locking of the escapement mechanism insures the proper position of the wheels 58 with regard to the matrices in the magazine when the escapement has been elevated into operative position therewith, as is clearly shown in Fig. 14. When the operator swings the actuator shaft 48 to lift the escapement,

the pins 93 will swing into the slots 92 of the dogs 89 and swing them upwardly about their pivots 90 and cause the universal latch 87 to swing outwardly in the eccentric slots 91, thus disengaging the latch 87 and unlocking the rotary escapement wheels 58. If desired, the weight of the basket structure carrying the escapement may be counterbalanced by coiling around the shaft 48 a spring 95, having one of its ends fastened to the shaft and its other end attached to the frame of the machine, the tension of the spring being such as to counterbalance, or tend to lift, the actuator-cams 69 and the basket structure. When the shaft 48 is actuated the basket rods 60 and 62 are lifted vertically by the cam slots 70, traveling upwardly until the upper member 60 tilts forwardly and upwardly into the curved slot-portion 67 of a bracket 65, and the lower member 62 advances into the transverse slot-portion 68. This action of the actuators upon the carriage structure is effective to carry the series of escapement wheels into register with their respective openings in the rear wall of that particular magazine which has been moved into position above a channel entrance B, Fig. 3. Approximately at the same instant that the pins 93 on the plates 69 enter the curved slots 92 of the dogs 89, a concentric edge 74' on that plate 69, on which is formed the rack 74, swings under a concaved surface 74^a cut in the periphery of the interrupted pinion 73. The purpose of this surface 74^a is to prevent the accidental rotation of the universal key 71 as the locking arm 76 is lifted upwardly by the pins 79, and when the locking arm 76 has been entirely freed from engagement with the key 71, the rack 74 will then intermesh with the pinion 73 and the continued movement of the actuator plate 69 will revolve the key to permit the escape of the matrices. After a line of type has been cast in the machine from matrices which have been collected from one of the magazines A, the matrices are then shifted to an elevator C, Figs. 1 and 2, by which they are carried upwardly to the distributor bar D.

The form of magazine and escapement mechanism which we have provided permit an increase of speed with which the matrices can be collected from the magazine, and since the escapement mechanism is not dependent upon any rotary-driven mechanism, but is controlled entirely by the release of a verge when the operator touches a key, it is advisable to provide an improved form of elevator mechanism which will operate at sufficient speed to equal the capacity of the escapement mechanism. To this end, we have shown the elevator C, which is a bar of the usual well known type in linotype machines, as attached to a bracket 100, guided upon suitable ways or 100.

rods 101, vertically supported upon the frame E, and the bracket 100 is carried upon a threaded nut 102 running on a spirally grooved shaft 103, Fig. 2, which is supported in suitable bearings and has secured upon its lower end a beveled gear 104, meshing with a complementary gear 105 secured upon a short shaft 106, which carries a pinion 107, meshing with a driving gear 108, secured upon a shaft 109. Power to drive the intermediate shaft 109 is derived from an annular rack 110, secured upon an arm 111, pivoted at 112 upon the frame, and which carries a cam-roller 113, resting upon a cam 114, which is secured to a driving shaft 115.

In operation, at suitable intervals, the cam 114 will rock the arm 111, causing the rack 110 to drive the shaft 109, from which motion is transmitted through the gears 107, 105 and 104 to revolve the screw-shaft 103, which will cause the bracket 100 to be elevated, carrying upwardly a line of suspended matrices 3. As the elevator is ascending, a trip 116 pivoted at 117 on the bracket 100, engages a projected arm 118 of a lever 119, which is pivoted at 120. The engagement of the trip 116 with the projecting arm 118, tilts backwardly the lever arm 119, which has connected to its upper end a link 121, pivoted on a sliding block 122, to which is secured a depending distributor shifter-slide 123. The function of the slide 123 is to shift the suspended matrices 3 from the elevator bar C to the distributor D, Fig. 2. The relative position of the trip 116 and the arm 119 is such that the distributor slide 123 will be carried to the left of the elevator bar C before the bar C has reached a position adjacent to the distributor bar D, and when the elevator is carried into line with the distributor bar D, the arm 118 will ride off of the trip 116, and a spring 124 connected to the lever 119 will immediately rock the lever 119 and force the slide 123 to the right, effecting the dislodgement of the matrices from the elevator to the distributor mechanism D. In order to prevent too rapid a motion of the distributor slide 123, any suitable brake may be employed to check the motion of the lever 119 under the impulse of the spring 124, and in this instance we have elected to show this brake as in the form of a dash-pot or air cushion 125, the piston of which is connected at 126 to the lever arm 119. During the descent of the elevator C, the trip 116 rides freely over the projecting arm 118 by tilting upon its pivot 117, as clearly shown in Fig. 6. For the purpose of cushioning the elevator C, when in upper position in line with bar D, we have interposed a spring 127, Fig. 4, between the nut 102 and the bracket 100.

From the foregoing it will be seen that with our present invention it will be pos-

sible for an operator to produce a greater number of lines in a given time, and have at his disposal a greater diversity of faces or fonts of type which is a desideratum, especially in advertising and job-work, and with our carriage removal or substitution of magazines on the carriage can be made while the machine is in use, without disturbing or interfering in any way with the composing of a line from a given magazine, and without interfering with the distribution of matrices to the same magazine. All of the magazines are adapted to be brought into registration with one common assembler entrance and distributing mechanism, thereby insuring a uniform length of time of arrival of matrices from any given magazine to point of assembling, or to the distribution of the matrices in the distributor, and our machine requires but a single complement of verges, reeds and controlling keys. Arranging the magazines vertically insures prompt and certain response of their matrices when a verge is rocked and it requires but a single movement to lock matrices in their magazines; to actuate the matrix-lock to latch the series of verges in fixed position; to disengage the escapement mechanism from co-operative position with a magazine and carry it downwardly out of the way of the shiftable carriage. After the escapement mechanism has been lowered, the operator simply has to pull on the handle 28, thereby disengaging the clutch 56 from the gear 54, and carrying into engagement with the gear 14 the pinion 14', after which, by turning the handle 28, the carriage shifting gear 8 engaging the rack 7 of the carriage may be turned until the desired magazine is carried into registration with the assembler entrance and distributor.

The magazines of our machine are designed to carry a full complement of matrices 3 of each letter, and the several magazines are simultaneously moved when the carriage F is shifted and a desired magazine can be brought into proper position in a very few seconds.

It will be seen that by this machine a saving is made in initial cost of erection and also that a reduction is made in operating expenses, where a number of fonts or faces are desired, by the saving of operators' time when making changes of fonts, thus leaving more time for keyboard work. The magazines may be removed and others inserted any time, either while the machine is in operation or idle.

Having thus described our invention, what we claim and desire to secure by Letters-Patent, is—

1. In a linotype machine, a carriage, interchangeable matrix magazines on the carriage, and a series of rotary escapements

- and supports therefor with which each magazine is adapted to be registered, said escapements and supports being bodily movable to permit shifting of the carriage.
5. 2. In a linotype machine, interchangeable magazines for matrices, a series of matrix-actuated rotary escapements, and a means for moving any one of the magazines into co-operative relation with the series of escapements, and for releasing said escapements after said movement of a magazine.
10. 3. In a linotype machine, a series of magazines for matrices, a set of rotary wheel escapements with which each of the said magazines may be registered, and a means for shifting said magazines for carrying the escapements into juxtaposition with the matrices in the magazine.
15. 4. In a linotype machine, matrix magazines, a shiftable carriage supporting said magazines, a matrix-actuated, rotary escapement mechanism with which each magazine may be registered, means for shifting the carriage and subsequently moving the mechanism into register with a magazine, and a distributor bar whereby matrices may be distributed to a magazine registered with the escapement mechanism.
20. 5. In a linotype machine, a plurality of removable magazines, a shiftable support therefor, a series of rotary, matrix-actuated escapements with which each of the magazines may be registered, a latch for the escapements, keys for supporting the matrices in the magazines when the latter are not in registration with the escapements, and a device for releasing the latch and operating a key of a registered magazine.
25. 6. In a linotype machine, a shiftable carriage, removable magazines supported thereon, locking devices to sustain matrices in the magazines, a series of rotary escapements, means for raising and lowering the escapements to permit the shifting of the magazine carriage, and instrumentalities for actuating the matrix locking device when the series of escapements is lifted into operative relation with one of the magazines.
30. 7. In a linotype machine, a shiftable carriage, a support therefor, means for shifting said carriage, magazines on the carriage having slots at one side, a series of escapements with which the slots in the magazines on the carriage can be individually registered, and means for locking the carriage in its shifted positions.
35. 8. In a linotype machine, a plurality of shiftable slotted magazines, a series of rotary escapements into registration with which any one of the magazines may be shifted so that the escapements enter the slots therein, means for bodily moving the series of escapements, instrumentalities for shifting the magazines, and a device for successively operating the escapement-moving means and the magazine shifting instrumentalities.
40. 9. In a linotype machine, a plurality of removable magazines, a shiftable carriage therefor, supports upon which said carriage may be shifted, means for shifting said carriage, a series of rotary escapements into co-operation with which each of the magazines may be carried, a bodily movable device supporting said series of escapements, mechanism for actuating said device, and an instrumentality for successively operating the carriage-shifting means and the escapement actuating device.
45. 10. In a linotype machine, the combination with a movable carriage, of magazines slotted at one side, a series of rotary escapement wheels registerable with the magazine slots, a plurality of verges co-operative with said wheels, a support whereby said members may be bodily moved into and out of registration with a magazine, means for actuating said support, and instrumentalities for controlling the operation of the verges when they are moved into co-operative relation with a magazine, said instrumentalities comprising reeds or links connected to finger-keys.
50. 11. In a linotype machine, a series of rotary escapement wheels, an arbor upon which said wheels are loosely mounted, a series of complementary verges, a bar upon which they are supported, plates in which said bar and said arbor are secured to form a bodily movable basket, means whereby said basket may be moved into engagement and disengagement with a magazine, and means for locking said escapement wheels and verges when moved out of engagement with the magazine.
55. 12. In a linotype machine, a series of rotary escapement wheels, an arbor upon which said wheels are loosely mounted, a series of complementary verges, a bar upon which they are supported, plates in which said bar and said arbor are secured to form a bodily movable basket, means whereby said basket may be moved into engagement and disengagement with a magazine, means for locking said escapement wheels and verges when moved out of engagement with the magazine, said means including a universal bar, and actuating arms whereby the bar is shifted laterally to be interposed between the escapement wheels and the verges.
60. 13. In a linotype machine, a series of rotary escapement wheels, an arbor upon which said wheels are loosely mounted, a series of complementary verges, a bar upon which they are supported, plates in which said bar and said arbor are secured to form a bodily movable basket, means whereby said basket may be moved into engagement and disengagement with a magazine, means

- for locking said escapement wheels and 65
verges when moved out of engagement with
the magazine, said means including a universal
bar, and actuating arms whereby the
5 bar is shifted laterally to be interposed be-
tween the escapement wheels and the verges,
and means for operating said arms.
14. In a linotype machine, a plurality of 70
removable magazines, a carriage therefor,
10 means for shifting said carriage, supports
upon which the carriage may be moved, de-
vices for locking the carriage in adjusted
position, a series of bodily movable esca-
pements, with which each magazine may be
15 registered, a key revolvably mounted in each
of the magazines for supporting and locking
the matrices therein, said key having an
interrupted gear formed on one of its ends,
an actuator for bodily moving the esca-
20 pements, and a rack attached to said actuator
for engaging the pinion on said key to re-
volve the latter and unlock the matrices
when the escapements are brought into oper-
ative relation with a magazine.
- 25 15. In a linotype machine, a plurality of 75
removable magazines, a carriage therefor,
supports upon which said carriage may be
moved, a rotary key in each magazine for
supporting the matrices therein contained
30 having a complementary lock portion, and
means for preventing the accidental rotation
of said key, said means comprising a pivoted
arm engageable and disengageable with
said complementary portion of said key.
- 35 16. In a linotype machine, a plurality of 80
removable magazines, a carriage therefor,
supports upon which said carriage may be
moved, a rotary key in each magazine for
supporting the matrices therein contained
40 having a complementary lock portion, means
for preventing the accidental rotation of
said key, said means comprising a pivoted
slotted arm engageable and disengageable
with said complementary portion of said
45 key, and means for carrying said arm out
of co-operative engagement with the key,
said means including a lever carrying a pin
adapted to engage the slotted portion of the
arm and lift the latter about its pivot.
- 50 17. In a linotype machine, a plurality of 85
removable magazines, a carriage therefor,
supports upon which said carriage may be
moved, a rotary key in each magazine for
supporting the matrices therein contained
55 having a complementary lock portion, means
for preventing the accidental rotation of
said key, said means comprising a pivoted
slotted arm engageable and disengageable
with said complementary portion of said
60 key, means for carrying said arm out of co-
operative engagement with the key, said
means including a lever carrying a pin
adapted to engage the slotted portion of the
arm and lift the latter about its pivot, and
65 instrumentalities whereby said key may be
rotated to release the matrices at the proper
time, said instrumentalities comprising a
lever-arm having an annular rack, and an
interrupted pinion secured upon said key to
rotate the latter when meshing with the 70
rack.
18. In a linotype machine, a shiftable 75
carriage supporting a series of movable
magazines, a series of escapements with
which the magazines may be moved into
registration, a distributor mechanism for the
distribution of matrices into any one of the
magazines, and a governor adapted to pre-
vent movement of the magazine carriage
while a matrix is suspended in the distribu- 80
ter mechanism.
19. In a linotype machine, a shiftable car-
riage, a plurality of removable magazines
mounted upon said carriage, instrumentalities
for shifting the carriage, a series of 85
escapements into registration with which
each of the magazines may be carried, means
for distributing matrices into the magazine
registering with the escapement, controlling
devices for said escapement, and governing 90
means to prevent the actuation of the car-
riage-shifting means while a matrix is sup-
ported on the distributing means.
20. In a linotype machine, a plurality of 95
removable magazines, a shiftable carriage
therefor, supports upon which said carriage
may be shifted, means for shifting said car-
riage, a series of escapements into coöper-
ation with which each of the magazines may
100 be carried, a bodily movable device support-
ing said series of escapements, mechanism
for actuating said device, an instrumentality
for operating the carriage-shifting means
and the escapement actuating device, and a
governor controlling said operating instru-
mentality.
21. In a linotype machine, a plurality of 105
removable magazines, a shiftable carriage
therefor, supports upon which said carriage
may be shifted, means for shifting said car-
riage, a series of escapements into coöper-
ation with which each of the magazines may
110 be carried, a bodily movable device support-
ing said series of escapements, mechanism
for actuating said device, an instrumentality
for operating the carriage-shifting means
and the escapement-actuating device, a gov-
ernor controlling said operating instru-
mentality, and a distributor bar whereby ma-
trices may be delivered into the magazine in 115
coöperation with the escapements.
22. In a linotype machine, a shiftable car-
riage supporting a series of interchangeable
magazines, a series of escapements with
which the magazines may be moved into
registration, a distributor mechanism for the
distribution of the matrices into any one 120
of the magazines, and a mechanism for mov-
125

ing and preventing the movement of the magazine carriage while a matrix of one of its magazines is in course of distribution, said mechanism consisting of an operating stem, a train of gears, one of which is mounted on said stem, and one of which engages said carriage whereby motion is transmitted from the stem to the carriage, and a detector coöperative with said operating stem and adapted to prevent the rotation of said stem when a matrix or matrices is suspended in the distributor mechanism.

23. In a linotype machine, a shiftable carriage supporting a series of interchangeable magazines, a series of escapements with which the magazines may be moved into registration, a distributor mechanism for the distribution of the matrices into any one of the magazines, a mechanism for moving and preventing the movement of the magazine carriage while a matrix of one of its magazines is in course of distribution, said mechanism consisting of an operating stem, a train of gears, one of which is mounted on said stem, and one of which engages said carriage whereby motion is transmitted from the stem to the carriage, and a detector coöperative with said operating stem and adapted to prevent the rotation of said stem when a matrix or matrices is suspended in the distributor mechanism, and a device for rendering the distributor mechanism inoperative when the stem is rotated.

24. In a linotype machine, a shiftable carriage for interchangeable magazines, a series of escapements coöperative with any one of the magazines, means for shifting the carriage to bring one or the other of the magazines into coöperative relation with said escapements, a distributor mechanism for distributing matrices to the selected magazine, and a device for rendering the distributor mechanism inoperative when the carriage is to be shifted, said device having a part co-operating with the carriage-shifting mechanism.

25. In a linotype machine, a shiftable carriage for interchangeable magazines, a series of escapements coöperative with any one of the magazines, means for shifting the carriage to bring one or the other of the magazines into coöperative relation with said escapements, a distributor mechanism for distributing matrices to the selected magazine, and a device for rendering the distributor mechanism inoperative when the carriage is to be shifted, said device having a part co-operating with the carriage-shifting mechanism for preventing the manipulation of said mechanism during the distribution of matrices from the selected magazine.

26. In a linotype machine, a shiftable carriage for supporting a series of interchange-

able magazines for matrices, an escapement mechanism into operative relation with which one of the magazines may be carried by the carriage, a device for shifting the carriage, and a governor controlling the operation of said device, said governor comprising a movable connector having one end designed for restraining engagement with a portion of said device and also designed for permitting the unrestrained operation of said device.

27. In a linotype machine, a shiftable carriage, a plurality of interchangeable magazines removable from the carriage, an escapement mechanism for controlling the release of matrices from a selected magazine, a distributor mechanism for returning matrices to the selected magazine, means for shifting the carriage to bring one of the magazines into coöordinate relation with said escapement mechanism and said distributor mechanism, a matrix detecting device mounted adjacent to the distributor mechanism, and a governor connected to said device and controlled thereby, said governor having coöperative relation with a part of the carriage-shifting means whereby, when said detecting device is unobstructed by a matrix or matrices in the distributor mechanism, the governor releases the carriage-shifting means to permit movement of the carriage, and said governor being controlled by said device when the latter is obstructed by a matrix to prevent the operation of the carriage-shifting means.

28. In a linotype machine, a shiftable carriage, a plurality of interchangeable magazines removable from the carriage, an escapement mechanism for controlling the release of matrices from a selected magazine, a distributor mechanism for returning matrices to the selected magazine, means for shifting the carriage to bring one of the magazines into coöordinate relation with said escapement mechanism and said distributor mechanism, a matrix detecting device mounted adjacent to the distributor mechanism, a governor connected to said device and controlled thereby, said governor having coöperative relation with a part of the carriage-shifting means whereby, when said detecting device is unobstructed by a matrix or matrices in the distributor mechanism, the governor releases the carriage-shifting means to permit movement of the carriage, and said governor being controlled by said device when the latter is obstructed by a matrix to prevent the operation of the carriage-shifting means, and an instrumentality controlled by the carriage-shifting means for moving the escapement into and from coöperative relation with a selected magazine on the carriage.

29. In a typographical machine, the com-

- bination of distributing mechanism, means to determine the presence or absence of type or matrices in normal position therein, and devices connected thereto to arrest the distributing mechanism. 5
30. In a typographical machine, the combination of a plurality of magazines, means for shifting the magazines, and distributing mechanism, with means coöperating with the distributing mechanism to prevent the shifting of the magazines and to arrest the distributing mechanism while any type or matrices of the magazine in position remain undistributed. 10
31. In a typographical machine, the combination of a plurality of magazines, means for shifting the magazines, and distributing mechanism, with a feeler to determine the presence or absence of type or matrices in the distributing mechanism, and connections to prevent the shifting of the magazines and to arrest the distributing mechanism while any type or matrices of the magazine in position remain undistributed. 15
32. In a typographical machine, the combination of a plurality of shiftable magazines, and distributing mechanism, with a manually operable feeler to determine the presence or absence of type or matrices in the distributing mechanism, and connections to prevent the shifting of the magazines and to arrest the distributing mechanism while any type or matrices of the magazine in position remain undistributed. 20
33. In a typographical machine, the combination of a plurality of magazines shiftable to bring one or another into operative position, distributing mechanism for the operative magazine, and means for automatically arresting the distributing mechanism when the magazines are shifted. 25
34. In a typographical machine, the combination of a plurality of magazines capable of independent use, distributing mechanism to deliver type or matrices to the magazine in use, and means whereby the mechanical selection of a different magazine automatically arrests the operation of the distributing mechanism and thus prevents the distribution of matrices to an improper magazine. 30
35. In a typographical machine, the combination of a movable magazine, distributing mechanism therefor, and means for automatically arresting the distributing mechanism when the magazine is moved. 35
36. In a typographical machine, the combination of a plurality of magazines, means for shifting the magazines to bring one or another into operative position, distributing mechanism for the operative magazine, and devices controlled by the magazine shifting means for arresting the distributing mechanism. 40
37. In a typographical machine, the combination of distributing mechanism, a movable magazine, means for moving the magazine, operating devices adapted to be connected to and disconnected from the magazine moving means, and means whereby the connection of said operating devices to the magazine moving means arrests the operation of the distributing mechanism. 45
38. In a typographical machine, the combination of a movable magazine, distributing mechanism therefor, and means to insure the arrest of the distributing mechanism before the magazine is moved. 50
39. In a typographical machine, the combination of a plurality of magazines, means for shifting the magazines, and distributing mechanism, together with means coöperating with the distributing mechanism to engage and hold the magazine shifting means against operation while any type or matrices of the magazine in position remain undistributed. 55
40. In a typographical machine, the combination of a plurality of magazines, means for shifting the magazines, and distributing mechanism, together with a feeler to determine the presence or absence of type or matrices in the distributing mechanism, and connections therefrom to the magazine shifting means to engage and lock them against operation while any type or matrices of the magazine in position remain undistributed. 60
41. In a typographical machine, the combination of a plurality of magazines, means for shifting the magazines, and a distributing mechanism, together with means coöperating with the matrices in the course of distribution to engage and hold the magazine shifting means against operation. 65
42. In a typographical machine, the combination of a magazine, means for shifting it, and a distributing mechanism, together with means to engage and hold the magazine shifting means against operation when matrices are present in the distributing mechanism. 70
43. In a typographical machine, the combination of distributing mechanism, a magazine, means for shifting the magazine, operating devices adapted to be connected to and disconnected from the magazine shifting means, and means to determine the presence or absence of matrices in the distributing mechanism, the said means being rendered active by the connection of the operating devices to the magazine-shifting means. 75
44. In a typographical machine, the combination of distributing mechanism, a vertically movable matrix feeler adapted to fall by gravity into the distributing mechanism, and means adapted to be tripped at will for holding the feeler up out of the distributing mechanism. 80
45. In a typographical machine, the com- 130

- bination of a distributor bar, and a U-shaped feeler straddling the bar and movable vertically to determine the presence or absence of matrices thereon.
46. In a typographical machine, the combination of a plurality of magazines shiftable to effect a change from one to another thereof, and a series of escapements movable into and out of operative relation to the active magazine.
47. In a typographical machine, the combination of a plurality of magazines shiftable to bring one or another into active position, a series of escapements movable into and out of operative relation to the active magazine, and means for locking the matrices in said magazine when the escapements are moved out of operative relation thereto.
48. In a typographical machine, the combination of a plurality of magazines shiftable to bring one or another into active position, a series of escapements movable into and out of operative relation to the active magazine, and means controlled by the movement of the escapements for locking the matrices in said magazine.
49. In a typographical machine, the combination of a plurality of magazines shiftable to bring one or another into operative position, and each provided with a locking device to retain the matrices therein, a series of escapements movable into and out of operative relation to the active magazine, and means whereby the movement of the escapements out of and into operative relation to a magazine will render its corresponding locking device active and inactive respectively.
50. In a typographical machine, the combination of a magazine, a series of escapements movable into and out of operative relation thereto, a locking device to retain the matrices in the magazine, automatic means for moving said device to active position as the escapements are moved out of operative relation to the magazine, and means for positively holding the locking device in its active position.
51. In a typographical machine, the combination of a magazine, a series of escapements movable into and out of operative relation thereto, a locking device for retaining the matrices in the magazine, means controlled by the movement of the escapements for operating the locking device, and an automatic latch for positively holding the locking device in its active position.
52. In a typographical machine, the combination of a magazine provided with a locking device for the matrices and a latch to hold said device in its active position, a series of escapements movable into and out of operative relation to the magazine, and automatic means for engaging and disengaging said latch and moving the locking device to active and inactive position as the escapements are moved from and to operative position respectively.
53. In a typographical machine the combination of a plurality of magazines shiftable to bring one or another into active position, and each provided with a locking device to retain the matrices therein, a series of escapements movable into and out of operative relation to the magazine, and common means for moving the escapements and operating the locking device of the active magazine.
54. In a typographical machine, the combination of a magazine provided with a locking device for the matrices and a latch for positively holding the said device in its active position, a series of escapements movable into and out of operative relation to the magazine, and common operating means for said escapements, locking device and latch.
55. In a typographical machine, the combination of a plurality of magazines shiftable to effect a change from one magazine to another, a series of escapements movable into and out of operative relation to the active magazine, and automatic means for locking the escapements against action when they are moved out of operative relation to said magazine.
56. In a typographical machine, the combination of a series of escapements movable to and from operative position, and a series of actuating members connected directly thereto, the said parts being formed so as to be automatically connected and disconnected as the escapements are moved to and from operative position.
57. In a typographical machine, the combination of a series of escapements movable at will from operative position, and a series of actuating members connected directly to the escapements, the said parts being formed so as automatically to be disconnected as the escapements are moved from operative position.
58. In a typographical machine, the combination of a movable magazine, a locking device to hold it in position, a series of escapements for the magazine, and common means for releasing said locking device and moving said escapements out of operative relation to the magazine.
59. In a typographical machine, the combination of a movable magazine, a locking device to hold it in position, a series of escapements movable out of operative relation to the magazine, and automatic means for releasing said locking device when the escapements are so moved.
60. In a typographical machine, the combination of a movable magazine, a locking device to hold it in position, a series of escapements movable into and out of opera-

tive relation to the magazine, and automatic means for moving said locking device to active and inactive position as the escapements are moved into and out of operative relation to the magazine, respectively.

61. In a typographical machine, the combination of a movable magazine provided with a locking device for the type or matrices, a locking device for holding the magazine in position, a series of escapements movable into and out of operative relation to the magazine, and common operating means for the escapements and said two locking devices.

62. In a typographical machine, the combination of a movable magazine provided with a matrix locking device movable to active and inactive position thereon, a locking device to hold the magazine in position, and common means for operating both said locking devices.

63. In a typographical machine, the combination of a movable magazine provided with a matrix locking device movable to active and inactive position thereon, a locking device to hold the magazine in position, and means whereby the release of said magazine locking device will move the matrix locking device to active position.

64. In a typographical machine, the combination of a series of escapements movable vertically to and from operative position, and means for counterbalancing the weight of the escapements in their vertical movement.

65. In a typographical machine, the combination of a magazine, means for shifting the magazine into and out of active posi-

tion, a series of escapements for the magazine, means for moving the escapements into and out of operative relation to the magazine, and common operating devices for both said means.

66. In a typographical machine, the combination of distributing mechanism, an elevator for delivering matrices thereto, a pusher for transferring the matrices from the elevator to the distributing mechanism, a spring for moving the pusher in one direction, and a pivoted lever for moving the pusher in the opposite direction, the said lever being operated by the elevator and adapted to be released thereby when the latter reaches its delivering position.

67. In a typographical machine, the combination of distributing mechanism, a vertically movable elevator for delivering matrices thereto, a pusher for transferring the matrices from the elevator to the distributing mechanism, a spring for imparting the transferring movement to the pusher, and a lever adapted to be engaged by the elevator in its upward movement for withdrawing the pusher against the action of the spring, the said elevator being formed with a movable part to allow the elevator to pass the lever in its downward movement.

In testimony whereof we have hereunto set our hands in the presence of two subscribing witnesses.
